UNITED STATES PATENT OFFICE.

HARRY B. WHITE, OF CANTON, OHIO, ASSIGNOR TO THE GILLIAM MANUFACTURING COMPANY, OF CANTON, OHIO, A CORPORATION OF OHIO.

BOW REST AND CLAMP DEVICE.

1,152,924.

Specification of Letters Patent.

Patented Sept. 7, 1915.

Application filed May 21, 1910. Serial No. 562,738.

To all whom it may concern:

Be it known that I, HARRY B. WHITE, a citizen of the United States, residing at Canton, in the county of Stark and State of Ohio, have invented certain new and useful Improvements in and Relating to Bow Rest and Clamp Devices, of which the following is a specification.

This invention relates to a bow rest and 10 clamping device adapted to facilitate the clamping of the bows of a collapsible vehicle top in folded or closed position, and the releasing of the bows when the top is to be raised.

15 For the purpose of illustration I have, in the accompanying drawings, shown and herein described one form of bow rest and clamp embodying my invention.

Figure 1 is an elevation of a portion of a 20 vehicle, showing a bow rest and clamp device embodying my invention, in operation. Fig. 2 is an elevation of the device. Fig. 3 is an elevation of the device looking toward the left of Fig. 2. Fig. 4 is a top plan view 25 of the device. Fig. 5 is a longitudinal sectional view of the upper portion of the device. Fig. 6 is a sectional view on the line 6—6 of Fig. 2. Figs. 7, 8 and 9 are fragmentary sectional views showing certain 30 parts of the device in different positions. Fig. 10 is a transverse sectional view on the line 10—10 of Fig. 6. Fig. 11 is a transverse sectional view on the line 11—11 of Fig. 8. Fig. 12 is a detail view. Fig. 13 is an elevation, partly in section, showing a different 35 form of bow rest and clamp device, embodying my invention, from that form illustrated in Figs. 1 to 12, inclusive. Fig. 14 is a front elevation, partly in section, of the bow rest 40 and clamp device illustrated in Fig. 13. Fig. 15 is a fragmentary view, partly in section. Fig. 16 is a sectional view of the cap or sleeve for closing the upper end of the standard. Fig. 17 is a top plan view of the 45 bow rest illustrated in Figs. 13, 14 and 15, with the upper clamp member displaced. Figs. 18 to 21 are detail views.

In the drawings, 1 indicates a vehicle body of any suitable or preferred construction.

50 2 indicates a collapsible top for the vehicle having bows 2^a which permit the collapsing and opening of the top as desired.

1^a indicates a bracket or arm carried by the vehicle body at either side thereof.

55 1^b indicates an opening, preferably of

conical shape, formed in the free end of the bracket.

3 indicates a combined rest and clamp device for the bows 2^a. This device 3 comprises a bow rest member 3^a and a bow clamp member 4 which is preferably movably or adjustably supported upon the rest member 3^a. The rest member 3^a comprises a rod 3^c depending from the bracket 1^a and preferably bent laterally at its lower end to form an arm 3^d which carries a bow rest plate 5. This plate 5 is provided with a collar 5^a through which the arm 3^d extends. The rest plate 5 is preferably adjustably secured to the arm 3^d by a set screw 5^b. The upper end of the rod 3^c is preferably reduced and extends through the opening 1^b of the bracket 1^a and is provided with screw threads to take a nut 3^e.

3^f indicates a conically shaped, split collar 75 surrounding the reduced end of the rod 3^c and fitting the opening 1^b of the bracket. It will be understood that by screwing down the nut 3^e the collar 3^f will be forced into close engagement with the reduced end of 80 the rod 3^c and thereby rigidly secure the rest and clamp device to the bracket 1^a.

The clamp member 4, in Figs. 1 to 12, inclusive, preferably comprises a supporting member 4' mounted on and adjustable up 85 and down on the rod 3^c and a clamp plate carrying member 6 movable longitudinally and angularly on the supporting member 4'. The supporting member 4' preferably comprises a standard or spindle 4^a having a collar 4^b, that slidably or adjustably fits the rod 3^c.

4^c indicates a recess formed in the inner wall of the collar 4^b and having an opening 4^c leading through the walls of the collar 95 to receive a cotter pin 4^d. One side of the cotter pin 4^d is concaved, as shown at 4^e, to engage with the adjacent face of the rod 3^c. A nut 4^f engaging the free end of the bolt and bearing against the adjacent face of the 100 collar, operates to tighten the cotter pin against the rod 3^c and thus secure it in any desired position along the rod 3^c. If desired, the standard 4^a may be formed separate and mounted in a socket 4^a of a base 4^a (see 105 Fig. 6). When constructed in this manner, the base 4^a and collar 4^b are formed integral.

The clamp plate carrying member 6 preferably comprises a casing 6' having a sleeve por- 110

tion 6^a which fits over and is slidably and rotatably mounted upon the standard or spindle 4^a. Preferably that portion of the standard 4^a which fits within the sleeve 6^a is reduced to 5 form a shoulder 4^a on which the sleeve rests and to make the outer walls of the sleeve and the base portion of the standard flush with each other. The upper portion of the casing 6^a is preferably enlarged to form a recess 6^b, and its walls thickened to accommodate and support parts of the interlocking devices, as will be later described.

6^c indicates an arm extending laterally from the casing 6^a and adapted to support 15 a clamp plate 6^d which engages with the uppermost bow of the collapsible top 2. The clamp plate 6^d and rest plate 5 co-operate with each other to lock or clamp the bows in folded position. The clamp plate 6^d is 20 preferably provided with a collar adjustably fitting over the arm 6^c. The collar is provided with a set screw 6^e for securing it to the arm 6^c.

7 indicates interlocking devices between 25 the clamp plate carrying member 6 and the spindle 4^a whereby the clamp plate 6^d is locked and clamped upon the uppermost bow 2^a and released therefrom, at will. These devices preferably comprise a trans- 30 versely extending recess 7^a formed in that side of the spindle 4^a adjacent the recess 6^b of the casing 6^a, and a cam 7^b operatively mounted in the recess 6^b, and arranged to engage one wall of the transverse recess or 35 slot 7^a.

7^c indicates a plate, to which the cam 7^b is secured, rotatably mounted in the recess 6^b. The cam 7^b is preferably formed integral with the rotatable plate 7^c, and ar- 40 ranged thereon to one side of its axis, so that when the plate is rotated the cam will be moved out of the recess 7^a and to one side of the spindle 4^a.

7^d indicates a shaft fixed to or formed in- 45 tegral with the plate 7^c.

7^e indicates a bearing member forming a bearing for the shaft 7^d, and provided with screw threads for engagement with the walls of an opening formed in the thick- 50 ened portion of the casing to receive the bearing member.

7^f indicates a handle or lever keyed to the outer end of the shaft 7^d. The bearing 55 7^e is preferably made large enough to occupy all the space between the opposing side faces of the plate 7^c and lever 7^f whereby all endwise movement of the shaft 7^d is prevented.

8 indicates a yieldable device, preferably 60 a spring, interposed between the casing 6^a and the upper or free end of the spindle 4^a. The casing 6^a is preferably closed at its upper end, as shown at 6^f. This closing end wall forms an abutment for the device 8. The free end of the spindle 4^a is

preferably provided with a stud 4^g around which the spring is coiled for securing the spring on the spindle. The casing 6^a carrying the locking cam 7^b and clamp plate 6^d may be bodily removed to permit the 7^a folding or closing of the top 2 and then replaced to clamp the bows upon the rest plate 5. Prior to replacing the casing 6^a in position the lever 7^f is thrown into a substantially vertical position so as to move 75 the cam 7^b to one side of or out of the path of the spindle 4^a, as shown in Fig. 7. After the casing is replaced, the lever is moved from the vertical to horizontal position, as shown in Figs. 2, 5 and 6. This 80 operation moves the cam 7^b into engagement with the upper wall of the slot or recess 7^a. This engagement of the cam 7^b and wall of the slot 7^a causes the casing 6^a and clamp plate 6^d to move downwardly in 85 opposition to the spring 8, the clamp plate engaging the uppermost bow 2^a and locking all of the bows 2^a upon the rest plate 5. It will be seen that the spring 8 serves to maintain the clamp plate carrying member 90 in a slightly elevated position, it being compressed when the interlocking devices are operated to lock the said member to the adjustable support 4^f. Thus this spring serves as an antirattler due to jars transmitted to the parts of the devices from the vehicle and also to elevate the clamp plate carrying member when released. The upper wall of the recess or slot 7^a is preferably inclined upwardly, as shown at 7^k, to 95 facilitate the engagement of the cam therewith.

Means are preferably provided for permitting the displacement of the upper clamp member into an abnormal position, 105 whereby the bows can be folded or unfolded without detaching said clamp member from the bow rest or its support. These means vertically guide the casing 6^a on the spindle 4^a and permit it to be elevated above 110 the bows 2^a and rotated about the spindle to move the clamp plate out of the path of the bows 2^a during their opening and closing operations. These means preferably comprise a longitudinally extending guide 115 slot or recess 9 formed in one side of the spindle 4^a, an annular recess 9^a into which the guide slot or recess 9 merges at its upper end, and a removable pin 9^b carried by the casing. The pin 9^b engaging with the 120 walls of the slot 9, operates to guide the casing 6^a, as it is lowered into position, so that the clamp plate 6^d will always align with the rest plate 5. By elevating the casing 6^a until the pin 9^b enters the recess 125 9^a, the casing 6^a may then be rotated about the spindle 4^a into the position shown in dotted lines in Fig. 4. It will be understood that through the engagement of the pin 9^b with the upper and lower walls of 130

the recess 9^a, the casing cannot be removed from the spindle 4^a, nor lowered, except when the pin registers with the upper end of the recess 9. By removing the pin 9^b, 5 the casing 6' can be entirely removed from the spindle.

Referring to Figs. 13, 14 and 15, 10 indicates a supporting member for supporting the clamp plate carrying member on the 10 bow rest member 3^a. This supporting member 10 may comprise a hollow member casing 10', having a collar portion 10^a slidably fitting over the rest plate supporting member 3. Preferably the collar 10^a is 15 curved forwardly and fits over the arm 3^a (see Fig. 13). 11 indicates the bow rest plate, having a collar 11^a, preferably fitting over the collar 10^a of the member 10. 10^b indicates an opening formed in the collar 20 10^a. 10^c indicates a set screw carried by the collar 11^a and extending through the opening 10^b, for securing the member 10 and rest plate 11 to the arm 3^a. The set screw 10^c permits the adjustment of the clamp 25 plate 11 and member 10 on the arm, or in directions toward and from the vehicle body 1. Preferably the opening 10^b formed in the collar 10^a is somewhat enlarged to permit relative movement between the rest 30 plate and the collar 10^a, within predetermined limits, whereby the bow rest plate may be slightly inclined to accommodate its bow engaging surface to the inclination of the lowermost bow 2^a of the vehicle top 2. 35 11^b indicates a pad, preferably formed of leather, fixed to the bow engaging surface of the rest plate 11, and operating to prevent abrasion of the adjacent bow 2^a. Preferably the opposite longitudinal edges 40 of the rest plate are bent over upon themselves, as indicated at 11^c, to clamp the pad in position. 10^d indicates the longitudinally extending opening or recess formed in the member 10 and adapted to receive a supporting bar or spindle 12 for a bow clamp plate 13. The bar 12 is bent forwardly, 45 preferably at right angles to form an arm 12', to which the clamp plate is adjustably secured by a screw 13^a. 13^b indicates a pad secured to the clamp plate 13. The opening 10^d is preferably enlarged to form a recess, as indicated at 10^e. The standard is 50 formed with an opening 10^f communicating with the recess 10^e, to accommodate and 55 support parts of the interlocking devices, as will be later described. 14 indicates the interlocking devices between the standard 10 and the bar 12, whereby the clamp plate 13 carried by the bar 12 is locked and clamped 60 upon the uppermost bow 2^a and released therefrom at will. These interlocking devices preferably comprise a transversely extending recess 12^a formed in that side of the bar 12 adjacent the recess 10^e of the stand- 65 ard 10, and a cam 14^a revolvably mounted in

the recess 10^e and arranged to engage one wall of the transverse recess or slot 12^a, to lock the bar 12 in operative position. 14^b indicates a plate, to which the cam 14^a is secured at one side of its axis, rotatably mounted in the recess 10^e. 14^c indicates a shaft fixed to or formed integral with the plate 14^b. 14^d indicates a bearing member having a screw threaded connection with the walls of the opening 10^f and forming a bearing for the shaft 14^c. 14^e indicates a handle or lever keyed to the outer end of the shaft 14^c. 15 indicates a collar surrounding the bar 12 and having screw threaded connection with the inner walls of the opening 10^d in the standard 10. The lower end of the bar 12 is preferably enlarged to form a flange 12^b, which engages with the collar 15 and prevents the removal of the bar 12 from the opening 10^d. The collar 15 is preferably arranged near the upper end of the opening 10^d to permit its ready insertion and removal by the use of a proper tool and also the raising of the bar 12 as far as possible in the operation of clamping and unclamping the bows 2^a. 10^g, 10^h indicate stops, preferably comprising lugs provided on the standard 10, operating to limit the throw of the lever 14^e in either direction. The clamp plate supporting bar 12 is preferably formed of two parts 12ⁱ, 12^k, to permit the adjustment of the clamp plate 13 relative to the rest plate 11. To carry out this purpose of the invention, the part 12ⁱ is formed with a screw threaded opening extending inwardly from its upper end and adapted to receive the lower end, which is screw threaded, of the part 12^k. 12^j indicates a nut, mounted on the part 12^k, and arranged, when screwed down into engagement with the upper end of the part 12ⁱ, to lock the parts 12ⁱ, 12^k in their adjusted position. 16 indicates a yieldable device, preferably comprising a coil spring, interposed between the standard 10 and the clamp plate supporting bar 12 and surrounding the latter as shown. 16^a indicates an inclosing sleeve, preferably formed integral with the lock nut 12^j and arranged to support the spring 16. Preferably the sleeve is formed with an internal flange 15^b which is turned over into engagement with one or more convolutions of the spring 16 and thus secures the latter within the sleeve 16^a.

As shown in Fig. 13, the sleeve 16^a is of a size to fit over the upper or free-end of the standard 10 and operates as a closing cap therefor. By this construction, the sleeve or cap 16^a keeps both dust and moisture from entering the opening 10^d and affecting the free operation of the interlocking devices and their deterioration.

It will be understood that by constructing the collar 11^a to fit over the collar 10^a of the stand-

standard 10 and connecting the rest plate 11 and standard 10 to the arm 3^d by a single securing device, the rest plate and clamp plate superposed thereabove can be adjusted 5 simultaneously toward or from the vehicle body 1, and thus adapt the devices to bows arranged at varying distances from the body of the vehicle to which they are applied.

When the cam is in operative position, as 10 shown in Figs. 5, 6, 13 and 14, the point of engagement of the cam with the clamp plate supporting member and the axis about which the cam revolves lie in a plane parallel to the direction of the forces acting against the 15 rest plate and clamp plate, that is, the cam occupies a "dead center" position, and thus effects a positive locking or clamping of the parts.

In the construction described all of the 20 sliding and interlocking or cam operating devices are entirely inclosed against dust and moisture.

In the operation of the device, assuming the parts to be locked in position and it is 25 desired to close and clamp the bows, the cam is operated into a position at one side of the clamp plate supporting or carrying member, as shown in Figs. 7 and 15. The clamp plate carrying part may now be elevated and rotated a quarter turn into the 30 position shown in Figs. 4 and 17, and the bows collapsed or folded, the lowermost bow resting directly upon the rest plate. The clamp plate may now be rotated back to its 35 former position and lowered, after which the cam is rotated, by the operation of the lever, into engagement with the wall of the slot, thus forcing the clamp plate closely against the uppermost bow. By first adjusting the clamp plate by means of its 40 vertically adjusting devices, the clamp plate can be positioned relative to the rest plate whereby upon the operation of the interlocking devices the bows will be rigidly 45 clamped between the rest plate and the clamp plate without placing undue strains upon any of the bows and at the same time preventing them from getting loose, or being jarred by the vehicle.

To those skilled in the art of making devices of the class described, many alterations in construction and widely differing embodiments and applications of my invention will suggest themselves, without departing from the spirit and scope thereof. My disclosures and the description herein are purely illustrative, and are not intended 55 to be in any sense limiting.

What I claim is:

60 1. The combination with a bracket adapted to be arranged on one side of a vehicle body, of a support carried by said bracket and carrying a bow rest, and bow clamping means bodily adjustable to said bow rest mounted on said support and carrying a bow

clamping plate to engage the uppermost bow, the said means comprising a support, a hollow casing arranged to receive the said support whereby one of said parts may be elevated relative to the other, and a lever 70 carried by the casing and connected to the support and arranged to operate and lock the clamping means in engagement with the uppermost bow.

2. In a device of the character described, 75 the combination of supporting means arranged to be supported at the side of a vehicle, two members mounted on said supporting means and coöperable to engage the upper and lower bows of a vehicle top, one 80 of said members being movable toward and from the other member, and means for connecting said members together in locked relationship, the said means comprising an engaging device carried by one of said members and a device carried by the other member and bodily movable into and out of the path of movement of said engaging device for engagement with and disengagement from said engaging device. 85

90 3. In a device of the character described, the combination of supporting means arranged to be supported at the side of a vehicle, two devices mounted on said supporting means and coöperable to engage the upper and lower bows of a vehicle top, one of 95 said devices being movable toward and from the other device, and means for locking said devices in operative relation, the said means comprising an engaging member carried by 100 one of said devices and a cam carried by the other device and bodily movable into and out of the path of movement of said engaging member for engagement with and disengagement from said member. 105

110 4. In a device of the character described, the combination of supporting means arranged to be supported at the side of a vehicle, two members mounted on said supporting means and coöperable to engage the upper and lower bows of a vehicle top, one 115 of said members being movable toward and from the other member, and means for locking said members in operative relation, the said means comprising an engaging member carried by one of said members, a rotatable member carried by the other member, a device mounted on said rotatable member and arranged to be bodily moved thereby into and out of the path of movement of said 120 engaging member, and means for operating said rotatable member.

125 5. In a device of the character described, the combination of a stationary member and a movable member coöperable to engage the upper and lower bows of a vehicle top, and means for drawing the said movable member toward the stationary member and positively locking the bows between them, the said means including a hollow casing carried by 130

one of said members, a cam swingably supported in said casing, and a standard or spindle fitting within said casing, whereby the casing and standard or spindle may slide 5 and rotate relative to each other, the said standard or spindle being provided with a recess to receive said cam, whereby the latter when swung in one direction operates to engage the walls of said recess and lock the 10 movable member in operable position and when moved in the other direction operates to free itself from said spindle.

6. In a device of the character described, the combination of a stationary member and 15 a movable member coöperable to engage the upper and lower bows of a vehicle top, and means for drawing the said movable member toward the stationary member and positively locking the bows between them, the said 20 means including a casing provided with a bearing, a shaft mounted in the bearing, a disk secured to the shaft, a cam carried by the disk, a spindle fitting within said casing and provided with a transverse recess the 25 walls of which said cam engages to lock the movable member in operative position, and a lever secured to the shaft for operating the said cam.

7. In a device of the character described, 30 the combination of a stationary member and a movable member coöperable to engage the upper and lower bows of a vehicle top, and means for drawing said movable member toward the stationary member and positively 35 locking the bows between them, the said means including a casing provided with a bearing, a shaft mounted in the bearing, a disk secured to the shaft, a cam carried by the disk, a spindle fitting within said casing 40 and provided with a transverse recess the walls of which said cam engages to lock the movable member in operative position, and a lever secured to the shaft for operating the said cam, the said casing being formed with 45 a recess to receive the cam and permit movement of the movable member away from said stationary member.

8. The combination with a bracket adapted to be arranged at one side of a vehicle 50 body, of a main support secured to said bracket and carrying a bow rest on which the bows of a top may be supported, an auxiliary support adjustable up and down on said main support relative to the bow rest, a bow clamping member movably mounted on said auxiliary support and provided with a plate for engaging one of the bows, and means for locking the clamping member to said auxiliary support for clamping the bows.

9. The combination with a bracket adapted to be fixed to one side of a vehicle body, of a main support secured to said bracket and carrying a bow rest on which the bows 55 of a top are supported when collapsed, an

auxiliary support adjustable on said main support, a bow clamping member movably mounted on said auxiliary member, and cam-operated means for locking the clamping member to said auxiliary support for 70 clamping the bows.

10. In a device of the character described, the combination with a bracket, of a main support depending from said bracket and provided with an arm at its lower end, a 75 rest adjustably mounted on said arm to move toward and from the vehicle, an auxiliary support movably mounted on said main support and arranged to be adjusted up and down thereon, means for securing the auxiliary support in its adjusted position on said main support, a member slidably and rotatably supported on said auxiliary support, the said member being provided with a plate arranged to engage a bow, and a cam carried 80 by said member and engaging said auxiliary support for drawing the member downwardly and holding it in a predetermined position with the plate in clamping engagement with a bow.

11. The combination with a bracket arranged at one side of a vehicle, of a support carried by said bracket and carrying a bow rest, and bow clamping means bodily adjustable relative to said bow rest mounted on 95 said support and carrying a bow clamping plate to engage the uppermost bow, the said means comprising a support provided with a transverse recess, a hollow casing arranged to receive the said support whereby one of 100 said parts may be elevated relative to the other, and a cam carried by the casing and movable into engagement with the walls of the recess in the support and arranged to operate and lock the clamping means in engagement with the uppermost bow.

12. In a device of the character described, the combination of two members coöperable to engage the upper and lower bows of a vehicle top, means for supporting one of 110 said members, an auxiliary support for supporting the other member and permitting it to move relative thereto, the said auxiliary support being adjustable up and down on said supporting means, means for 115 securing the auxiliary support in its adjusted position, and a cam for moving said movable member relative to the auxiliary support toward the other member and holding it in engagement with an adjacent bow.

13. In a device of the character described, the combination of two members coöperable to engage the upper and lower bows of a vehicle top, means for supporting one of 120 said members, an auxiliary support for supporting the other member and permitting it to move relative thereto, the said auxiliary support being adjustable up and down on said supporting means, means for securing the auxiliary support in its adjusted posi- 13

tion, a cam for moving said movable member relative to the auxiliary support toward the other member and holding it in engagement with an adjacent bow, and a yieldable device interposed between the auxiliary support and the movable member arranged to be compressed when the cam is operated.

14. In a bow rest and clamp device, the combination of two members coöperable to engage the upper and lower bows of the vehicle top, a support for one of said members, an auxiliary support for the other member adjustably mounted on the first mentioned support and permitting the adjustment of one member relative to the other member, the said auxiliary support permitting angular and longitudinal movements of the movable member relative to the auxiliary support independently of the adjustment thereof on said support, a cam for positively moving the movable member toward the other member and locking it in engagement with the adjacent bow, and means for alining said movable member prior to the operation of the cam.

15. In a bow rest and clamp device, the combination of a pair of bow engaging members, one of said members being movable toward and from the other member and coöperable therewith to clamp a set of bows between them, means for clamping said members in operative relation, and means for guiding the movable member toward and from the other member and permitting angular adjustment of said movable member when moved to a predetermined position.

16. In a bow rest and clamp device, the combination of a pair of bow engaging members, one of said members being movable toward and from the other member and coöperate therewith to clamp a set of bows between them, means for clamping said members in operative relation, and means for guiding the movable member toward and from the other member and permitting angular adjustment of said movable member when moved to a predetermined position, the said guiding means operating to detachably secure said members together.

17. The combination of a bow rest, means adapted to support the bow rest from a vehicle body or frame, an auxiliary support, means for adjustably connecting the auxiliary support to said supporting means, a hollow casing provided with an arm slidably mounted on said auxiliary support, a bow clamp carried by the said arm to coöperate with the bow rest, and cam-operated means between the casing and the auxiliary support for drawing the casing downwardly and clamping the clamp carried thereby in operative position.

18. The combination of a bow rest, means

for supporting the bow rest from the vehicle body or frame, a standard formed with a recess, means for adjustably supporting the standard on the supporting means, a casing slidably mounted on the standard and carrying a bow-engaging clamp, and means carried by the casing engaging the walls of the said recess for moving the casing downwardly to operate the clamp.

19. The combination of a bow rest, means for supporting the bow rest from the vehicle body or frame, a standard formed with a recess, a casing slidably mounted on the standard and carrying a bow-engaging clamp, a cam engaging with the walls of the said recess for moving the casing downwardly, and means for revolubly supporting and operating the cam.

20. The combination of a bow rest, means for supporting the bow rest from the vehicle body or frame, a standard, a bow clamp device movably mounted on the standard, and arranged to coöperate with the bow rest, locking means between the clamp device and the standard for clamping the bow clamp device in operative position, and means detachably connecting the clamp device to the standard and operating to guide the clamp device when moved vertically and for supporting it in an elevated position.

21. In a bow clamping device, the combination of a supporting member having an arm, a rest plate mounted thereon and adjustable laterally relative thereto, a standard carried by and vertically adjustable on the supporting member, a clamp plate, a clamp plate supporting means slidably mounted on the standard, the said clamp being movable on its supporting means in lateral directions and cam operated means between the standard and the clamp plate supporting means for clamping the said clamp plate in operative position.

22. In a device of the character described, the combination with a bracket adapted to be supported at the side of a vehicle, of a rod secured to and depending from said bracket and provided with a horizontal arm at its lower end, a member adjustable up and down on said rod, means for securing the said member in any position on said rod, a separate rod slidably supported on said member and provided with a horizontal arm at its upper end, the said arms being provided with plates to engage the upper and lower bows of the vehicle top, means for normally maintaining the separate rod in an elevated position, and means for drawing said separate rod downwardly to effect a clamping action upon the bows in opposition to said elevating means.

23. In a device of the character described, the combination with a bracket adapted to be supported at the side of a vehicle, of

a rod supported by said bracket and provided with a horizontal arm at its lower end, a member adjustable up and down on said rod, means for securing the said member in any position on said rod, a separate rod slidably supported on said member and provided with a horizontal arm at its upper end, the said arms being provided with plates to engage the upper and lower bows of the vehicle top, cam means for drawing said separate rod downwardly to effect a clamping action upon the bows, and a yieldable device permitting the cam to operate.

24. In a device of the character described, the combination of a vertically depending rod arranged to be supported from the side of a vehicle, a separate rod arranged parallel to the other rod, means interposed between the rods for connecting them together and supporting the separate rod on the supported rod, the said connecting means being adjustable up and down on said supported rod and permitting the said separate rod to move up and down and angularly relatively to said connecting means and independently of its adjustment on said supported rod, means for securing the connecting means in any position on the supported rod, plates carried by said rods arranged to engage the upper and lower bows of the vehicle top, and means for moving said separate rod downwardly into operative position and for locking it in said position.

25. For a vehicle provided with a folding top, a bow rest comprising, a stationary vertical post, a movable vertical post and a member connecting said posts, said stationary post and said movable post each provided with a bow engaging jaw, said connecting member adapted for vertical sliding movement on said stationary post, means for locking said connecting member and stationary post against relative sliding movement and means for vertically slidably moving said movable post with relation to said connecting member.

26. For a vehicle provided with a folding top, a bow rest comprising a stationary vertical post, a movable vertical post and a member connecting said posts, both of said posts provided with bow engaging jaws, said connecting member adapted for vertical sliding movement with relation to both

of said posts, and independent means for locking each post against such relative sliding movement.

27. For a vehicle provided with a folding top, a bow rest comprising a stationary vertical post, a movable vertical post and a member connecting said posts, both of said posts provided with bow engaging jaws, said connecting member adapted for vertical sliding movement with relation to both of said posts, and means for locking said member against vertical sliding movement with reference to one of said posts, and independent means for vertically slidably moving the other post with reference to said member.

28. For a vehicle provided with a folding top, a bow rest comprising a vertical stationary post provided with an integral horizontal arm having a bow engaging jaw, a movable vertical post provided with an integral horizontal arm provided with a second bow engaging jaw, and a member vertically slidably connected to both of said posts, means for locking said connecting member against vertical sliding movement with one of said posts, and cam-actuated means for vertically slidably moving the other of said posts with reference to said connecting member.

29. For a vehicle provided with a folding top, a bow rest comprising, a stationary, vertical post provided with a lower jaw adapted to receive the bows of the top when in folded position, a movable, vertical post provided with an upper jaw, a connecting member, said connecting member vertically slidably connected to said stationary post, and said movable post vertically slidably and horizontally rotatably connected to said connecting member, means for locking said connecting member against movement with relation to said stationary post, and means for locking said movable post against movement with relation to said connecting member.

In testimony whereof I affix my signature, in the presence of two witnesses.

HARRY B. WHITE.

Witnesses:

J. F. T. WALKER,
CHAS. M. BALL.

It is hereby certified that in Letters Patent No. 1,152,924, granted September 7, 1915, upon the application of Harry B. White, of Canton, Ohio, for an improvement in "Bow Rest and Clamp Devices, errors appear in the printed specification requiring correction as follows: Page 7, line 90, claim 29, for the word "conneting" read *connecting*; same page, line 93, same claim, for the word "oennected" read *connected*; and that the said Letters Patent should be read with these corrections therein that the same may conform to the record of the case in the Patent Office.

Signed and sealed this 28th day of September, A. D., 1915.

[SEAL.]

J. T. NEWTON,

Acting Commissioner of Patents.
